UNITED STATES PATENT OFFICE

KENNETH JACKSON, OF ST. ALBANS, NEW YORK, ASSIGNOR TO OHMER FARE REGISTER COMPANY, OF DAYTON, OHIO

COIN BOX

Application filed June 30, 1928. Serial No. 289,490.

The object of this invention is to provide a new and novel coin receiving receptacle known as a fare box, which is enclosed by means of four transparent sides and having the conventional coin receiving opening at the top. The specific purpose of the invention is to provide a mechanism whereby the operator will have a double visualization of the coin or coins deposited in the fare box before they finally enter the locked coin receiving compartment placed below the mechanism.

Frequently, the coins deposited in devices heretofore known were subject to dispute. In rush periods the coins may be deposited so rapidly that the operator cannot distinguish what coins were last deposited. In my improved construction I have provided a plurality of coin receiving trays so that the operator can cause the coins to successively pass from one tray to the next and is thereby enabled to visualize what coins have been deposited.

In devices heretofore known there has been only one coin receiving tray and when the operator tilted that tray the coin passed directly into the locked box where the coin could not be seen. Disputes sometimes arose as to what coin or coins were deposited. In my improved construction the coin does not directly pass into the locked department but passes to another tray where it can be seen and disputes are thereby avoided.

With these and other objects in view I have shown my invention by way of illustration in the attached drawings forming a part of this specification in which—

Fig. 1 is a side elevational view thereof partly in cross-section.

Fig. 2 is a cross-sectional plan view on the line 2—2 of Fig. 1, and

Fig. 3 is a cross-sectional elevational view on the line 3—3 of Fig. 2.

The locked compartment 1 is of conventional construction and receives the coins from the coin box. Mounted on the top of the locked compartment 1 are four standards 2 composed of angle iron which form corner posts for the glass sides 3 which are four in number, so that the coins may be seen from

every side. A shaft 4 passes through the two opposite sides of the locked compartment 1, which shaft is provided with an operating handle 5 and with an arm 6 extending in an opposite direction from the handle 5. A coin receiving tray 7 is rigidly secured to the arm 6 and normally closes an opening 8 in the top 9 of the locked compartment. An arm 10 is secured to the upper face of the coin tray 7, which arm is provided with a lug 11 which engages one of the sides of the top plate 9 so as to limit the downward movement of the coin tray 7 when the handle 5 is raised.

A frame 12 is secured to the top 9 of the locked compartment, which frame consists of four plates 13 which have their upper ends secured to a band 14. The plates 13 are rectangular in cross-section and lie parallel to the standards 2. Each of the rear plates 13 carry side plates 15 which plates are connected by means of a top plate 16 and a front plate 17 which is arcuate in shape as clearly shown in Fig. 3. Each of the side plates 15 are provided with slots 18 which receive pins 19, which pins are carried by the upper end of the rear wall 20 of a coin receiving tray having a bottom wall 21 and sidewalls 22. This coin receiving tray is pivoted on the arms 10 by means of pins 23 which extend through lugs 24.

The front plates 13 have brackets 25 secured thereto which are provided with pins 26 which support the top coin receiving tray 27 which consists of a front wall 28, a bottom wall 29 and sidewalls 30. The bottom wall 29 is provided with rearwardly extending fingers 31 which engage beneath shoulders 32 of the top wall 16 heretofore described. The arms 10 normally engage the fingers 31 and hold the top tray 27 in the position shown in full lines in Fig. 1.

On top of the standards 2 is mounted a conventional cap 33 having a coin hopper 34.

In operation the coin or coins are deposited in the opening in the cap 33 and readily pass through the coin hopper 34 onto the bottom wall 29 of the top tray 27. If any of the coins should strike the top plate 16 they would be deflected into the tray 27 where

they remain until the operator raises the handle 5. As the coins rest in the top tray they can be readily seen by looking through any one of the four glass sides 3. When the operator raises the handle 5 he moves the various parts into the dotted line position shown in Fig. 1, the arms 10 moving forwardly so that the top tray 27 drops by gravity and the bottom wall 21 of the second tray moves forwardly and upwardly to the position shown in Fig. 3 so that the coins pass from the top tray into the second tray and now repose on the bottom wall 21 where again they may be seen from any position. The arcuate front plate 17 prevents the coins reaching the tray 27 until after the tray passes below the lower extremity of the said front plate 17. Such a construction will prevent the coins overshooting the second tray and will insure that they are deposited therein. When the operator releases the handle 5 the parts resume their positions shown in full lines in Fig. 1 because the operating handle 5 is considerably heavier than the coin tray 7, arms 10 and parts associated therewith. During this movement of the parts the pins 23 move rearwardly so as to lower the bottom wall 21 of the metal tray and deposit the coins on the coin tray 7 where again they may be inspected. When the operator again raises the operating handle 5 the bottom tray 7 will drop to its dotted line position and the coins resting thereon will be deposited in the locked compartment 1.

It is obvious that by the use of the construction shown herein the coins will be visually displayed three times and that the operator must raise the handle 5 twice in order to pass the coins from the top tray into the locked compartment.

While I have shown the preferred construction of my invention I fully realize that many changes may be made in the specific embodiment thereof and I, therefore, do not desire to limit myself to the specific construction shown herein except as I may limit myself in the annexed claims:

1. In a coin receiving box, an operating handle, a tray operatively secured thereto, arms carried by said tray, a second tray having a fixed pivot at one end thereof and having its other end supported by said arms, said arms being removed from supporting said second tray in elevated position when said handle is raised so as to permit said second tray to fall by gravity and to drop the coins deposited therein.

2. In a coin receiving box, a handle normally positioned in a substantially horizontal plane, upstanding arms connected to said handle and a tray pivoted at one end to a fixed support and normally supported at its other end by said arms, said arms sliding toward said pivoted end when said handle is raised and permitting said tray to fall by

gravity so as to drop the coins deposited therein.

3. In a coin receiving box, a handle normally positioned in a substantially horizontal plane, upstanding arms connected to said handle, a tray pivoted at one end to a fixed support and normally supported at its other end by said arms, said arms sliding toward said pivoted end when said handle is raised and permitting said tray to fall by gravity so as to drop the coins deposited therein, and means to prevent the coins leaving said tray until the tray has been lowered to a predetermined extent.

4. In a coin receiving box, an operating handle, arms operatively connected to said operating handle, a tray pivoted to said arms, fixed guides, and pins carried by said tray and extending into said guides so as to cause said tray to be tilted upwardly when said handle is raised and to be lowered when said handle is lowered.

5. In a coin receiving box, an upper, lower and metal tray, an operating handle, said lower tray being operatively connected to said operating handle so as to move in unison therewith, arms carried by said lower tray, said metal tray being operatively connected to and supported by said arms, fixed guides, and pins carried by said last mentioned tray extending into said guides, the upper tray being pivotally mounted at one end and supported at its other end by said arms.

In testimony whereof I affix my signature.

KENNETH JACKSON.
